UNITED STATES PATENT OFFICE.

EDWARD ALFRED GRAHAM, OF BROCKLEY, LONDON, ENGLAND; MARIA GRAHAM AND ALFRED GRAHAM EXECUTORS OF SAID EDWARD ALFRED GRAHAM, DECEASED.

SWITCH APPARATUS FOR USE WITH TELEPHONIC RECEIVERS.

Application filed February 18, 1926, Serial No. 89,180, and in Great Britain September 7, 1925.

When a loud speaking telephone is to be used in conjunction with a multi-valve wireless receiving set, the steady current flowing in the plate circuit of the last valve of a series of valves, commonly flows through the telephone windings. Under some circumstances, where for instance the actual plate current is high in value, such being particularly the case when power valves are employed for use in low frequency amplification, it is advantageous to provide a shunt path for the continuous current component so that only the fluctuatory component, alternating in character, flows in the telephone windings. For this purpose, it is common practice to incorporate in the output leads of a wireless receiving set, a series of connections known as a "filter circuit", which provides a choke coil or inductance directly across the output terminals, the said choke coil or inductance being bridged by the telephonic windings in series with a condenser of appropriate capacity, so as in effect to allow only the modulated telephonic current to pass through to the telephone receiver or receivers and to "filter off" the steady direct current component therefrom. Such "filter circuits" and their application are generally well known and no claim is herein made to the use per se of such a circuit.

This invention has for its object to provide means whereby may be tested or compared, relative to each other, or to one, which may be a standard, a number of telephonic receivers adapted collectively or singly to be connected in circuit with any one of a number of wireless receiving sets in the output leads of which may or may not be incorporated a "filter circuit" adapted for the purpose hereinbefore stated. A further object of the invention is to provide an improved switching arrangement or apparatus for use with a "filter circuit", whereby the telephonic current can be applied to one, or to a number of telephonic receivers, which advantageously may be of the loud speaker type, and whereby also the "filter circuit" is or can be switched into or out of circuit at will.

To this end, switch apparatus according to the invention comprises a frame or holder adapted to house therein the capacity and inductance of the filter circuit and some of the other necessary components and their circuit modifying and making and breaking

means, one of the bounding planes of said frame or holder, constituting a panel, being made of insulating material adapted to carry all or most of the component parts, including the necessary switches, terminals and wiring, to enable the object of the invention to be attained in a simple and effective manner.

In the accompanying drawings, Fig. 1 is a plan of one construction of switch apparatus according to the invention. Fig. 2 is an underside view of the top panel of such apparatus carrying the component parts thereof. Fig. 3 shows partly in vertical section and partly inside elevation a detail. Fig. 4 is a vertical section on the line IV—IV of Fig. 2. Fig. 5 represents in side elevation, an interchanging switch shown in Fig. 2, the switch being shown in its mid or "off" position in both figures. Figs. 6 and 7 are underside views of the said switch in two opposite closed positions. Fig. 8 shows, diagrammatically, a modified construction of the switch apparatus.

According to the example shown in Figs. 1 to 6 inclusive, the frame or holder for the assembly of the parts mentioned, comprises a box 1 having side walls and a bottom of wood, and a top or closure 2 made of ebonite adapted to be detachably secured to the box, as by screws 2^a, and constituting a panel to the underside of which is attached a choke-coil 3 and a condenser 4, for the filter circuit, and also the contact members of switching means, together with the wiring for connecting the various parts in proper relationship, so that when such a panel is secured to the box, the said parts carried thereby will be situated within the box except parts of the switch operating levers. On the outside of the panel are mounted terminals for connection to the output leads from a wireless set or sets and also pairs of terminals for the connection of telephone leads. In the example shown, there are two pairs of terminals 5—5^a and 6—6^a for connection to the output leads of two wireless sets, and six pairs of terminals 7, 7^a for connection to six pairs of telephone receivers. Extending through slots 8 in the panel 2 and pivoted in bearings 9 carried by the panel, are a number of switch levers 10 for operating the circuit making and breaking contacts of switches located within the box.

These switches, for controlling the circuit

of telephone receivers, connected across the pairs of terminals 7—7^a, are, according to the example shown, formed of conducting spring wire, each of such switches (herein-
5 after called telephonic switches) comprising two separated but adjacent contact members or fingers 11 and 12 of unequal length clamped between two discs 14 of insulating material, as for instance ebonite, the ar-
10 rangement being such that when the inner end 10^a of the corresponding switch lever 10, which is of conducting material and forms a movable contact, is in its off-position, that is to say, when it is intended that
15 it shall not complete a circuit controlled thereby, it is touching the free end, of the longer spring finger 12 only, as shown in full lines in Fig. 2, but when it is desired to complete the circuit, it can be moved
20 through an angle, in a plane perpendicular to that of the panel 2, by means of the lever handle 10^b situated outside the box, and be brought as shown in dotted lines in Fig. 2, into contact with both of the spring fingers
25 11 and 12 between which it is arranged to work. The other end 11^a of the spring member 11, is connected to the inwardly projecting stem of one, namely 7^a, of one of the pairs of terminals 7—7^a on the outside
30 of the panel 2 and the other end 12^a of the spring member 12 is connected to an inner conducting wire 13 which is common to all the telephone switches. Such a telephone switch is secured to the underside of the
35 panel 2, as by a screwed stem 2^a secured to the panel 2 and extending in a downward direction and passing through the centre of the two ebonite discs 14 between which the spring wire members 11, 12 are firmly
40 clamped by screwing a nut 2^b on the screw. In order that the spring members 11—12 may take a snug and secure seating between the discs and in order to prevent them touching each other, or the screw 2^a ex-
45 tending between them, one disc may as shown in Fig. 4, be formed on its clamping surface with two substantially semi-circular opposed grooves 14^a—14^b of a depth sufficient to admit of the housing of the said
50 wire members and yet ensuring a firm clamp. The other terminal 7 of the pair of terminals 7—7^a for each switch is connected to another inner conducting wire 15 common to them and connected to the other main ter-
55 minal 5^a of the switch apparatus.

The mounting of the switch levers 10 may be effected by providing each of them at an intermediate portion of its length with a cross pin 10^c (Fig. 3) pivotally mounted
60 between a metal plate 16 and the underside of the insulating panel 2 which is notched at 17 to accommodate the ends of the said pin. The panel may have inscribed thereon directions for moving the lever in order to
65 make or break circuit.

A telephonic receiver can be connected across the pair of terminals 7, 7^a corresponding to any of the switches by means of which the said receiver can be put in and out of circuit as required.

A control switch is provided whereby the "filter circuit" can be put in and out of action as may be desired. A switch for this purpose may comprise, as shown, three stationary spring wire contact members 18, 19 and 20 and a movable contact 21 carried by the lower end of a control lever 22 pivoted to the panel 2 and extending through a slot 23 therein to and above the upper surface thereof. The wire contact members 18, 19 and 20 have intermediate curved portions 18^a, 19^a and 20^a clamped between two plates 24 of ebonite by means of a screw 25 and nut 26, like the two spring wire members 11 and 12 for each telephonic switch herein-
70 before described. These stationary spring contact members are connected up in the manner hereinafter described.

As in the example now being described, two pairs of terminals 5, 5^a and 6—6^a are provided for connection to two separate wireless sets, either of which can be used at will, interchanging switch mechanism is necessary whereby either of the wireless sets can be switched into use at will. Conveniently, a single interchanging switch may be used for the purpose. In the example shown in Figs. 2, 5, 6 and 7, the interchanging switch comprises two relatively short stationary upper spring contacts 27 and 27^a each having a bent free end, two longer stationary lower spring contacts 28 and 28^a each having a bent free end, two relatively long stationary upper spring contacts 29, 29^a and two insulated coaxially arranged cylindrical movable contacts 30 and 30^a. The stationary contacts are clamped between three discs 32 of insulating material for instance ebonite, in such manner that they are insulated from one another. The movable contacts 30 and 30^a are carried by but insulated from a lever 31 pivoted to the panel 2 and extending through and above the same. Contacts 27, 28 and 29 are arranged to co-act with the movable contact 30, and contacts 27^a, 28^a and 29^a are arranged to coact with the movable contact 30^a. Contacts 27 and 27^a are connected to the terminals 5 and 5^a respectively and contacts 28 and 28^a are connected to the terminals 6 and 6^a respectively. Contact 29 is connected to one pole 4^a of the condenser 4 and to the contact 18 of the control switch and contact 29^a is connected to the conductor 15 to which the terminals 7 are connected, and to one terminal 3^a of the choke coil 3. Contact 19 of the control switch is connected to the conductor 13 to which the contacts 12 of the several telephonic switches are connected and also to the pole 4^b of the condenser 4. Contact 20 of the control switch
75 80 85 90 95 100 105 110 115 120 125 130

is connected to the second terminal 3^b of the choke coil. With the movable contact 21 in the position shown in full line in Fig. 2, namely between contacts 18 and 19 the condenser 4 is short circuited and the circuit of the choke coil is open so that both of these devices are then out of use. When the movable contact 21 is moved into the position shown in dotted lines in which it is between contacts 18 and 20, the condenser 4 is connected in series with the conductor 13, one or more of the telephone switches 10, 11, 12, one or more telephones connected across one or more pairs of terminals 7, 7^a and conductor 15, this circuit being connected across one or other of the pairs of terminals 5, 5^a or 6, 6^a or being open. With the lever 31 of the interchanging switch in the mid or "off" position shown in Figs. 2 and 5, contacts 29 and 29^a alone bear on the movable contacts 30 and 30^a so that both sets of terminals 5, 5^a and 6, 6^a are electrically disconnected from the rest of the apparatus. When the lever 31 of the interchanging switch moves the contacts 30, 30^a into the position shown in Fig. 6, contact 27 bears on contact 30 upon which contact 29 simultaneously bears, and contact 27^a bears on contact 30^a upon which contact 29^a simultaneously bears, so that the telephone switches and terminals 7 are connected across the set of terminals 5—5^a. When the lever 31 moves the contacts 30, 30^a into the position shown in Fig. 7, the bent end of contact 28 bears on contact 30 upon which contact 29 simultaneously bears, and contact 28^a bears on contact 30^a upon which contact 29^a simultaneously bears, so that the telephone switches and terminals 7 are then connected across the second set of terminals 6, 6^a.

In the modified construction shown in Fig. 8, only one set of terminals 5, 5^a is provided so that no interchanging switch is necessary. In this, the contact 18 of the control switch is connected to the terminal 5 and to one pole 4^a of the condenser 4 the other pole 4^b of which is connected to the conductor 13. The contact 19 is connected to one terminal 3^a of the choke coil 3 the other terminal 3^b of which is connected to the terminal 5^a to which is also connected the conductor 15 to which the terminals 7 are connected. Contact 20 is connected direct to the conductor 13 to which the contacts 12 of the telephone switches 10, 11, 12 are connected. When the movable contact 21 is moved into the position shown in full lines, the choke coil 3 and condenser are connected for use, and when it is moved into the position shown in dotted lines, the choke coil and condenser are put out of use.

The terminals 7, 7^a mounted on the outside of the panel 2 may be connected to the conducting wires 13 and 15 within the box 1 by soldering their stems, which extend through

the panel, to the desired points of the wires 13 and 15.

For the sake of easy distinction, the terminals 7, 7^a are referred to in the claims as telephone terminals, and the terminals 5—5^a, 6—6^a and 6—6^a are, for a like reason, referred to in the claims as wireless terminals.

What I claim is:

1. Switch apparatus for use with telephonic receivers and wireless apparatus, comprising a support, pairs of insulated telephone terminals carried thereby, an insulated pair of wireless terminals carried by said support, a choke coil, a condenser, telephone switches and a control switch, each telephone switch being adapted to close and open a circuit between the pair of wireless terminals through a telephonic receiver connected to the corresponding pair of telephone terminals and the control switch being adapted in one position to connect the choke coil across the pair of wireless terminals and connect the condenser in series circuit with each telephone circuit closed by a telephone switch and in another position to put the choke coil and condenser out of use and enable each telephone circuit to be connected across the pair of wireless terminals.

2. Switch apparatus for use with telephonic receivers and wireless apparatus, comprising a support, pairs of insulated telephone terminals carried thereby, pairs of insulated wireless terminals carried by said support, for connection to independent wireless sets, a choke coil, a condenser, telephone switches, a control switch and interchanging switch means, each telephone switch being adapted to close and open a circuit between one or other pair of wireless terminals and a telephonic receiver connected to the corresponding pair of telephone terminals, the control switch being adapted in one position to connect the choke coil across one or other of the pairs of wireless terminals and place the condenser in each telephone circuit closed by a telephone switch and in another position to put the choke coil and condenser out of action and enable each telephone circuit to be connected across one of the pairs of wireless terminals and the interchanging switch means being adapted to connect one or other of the pairs of wireless terminals to the circuits controlled by the telephone switches and control switch.

3. Switch apparatus for use with telephonic receivers and wireless apparatus, comprising a support, pairs of insulated telephone terminals carried thereby, a pair of insulated wireless terminals carried by said support, conducting means between one of the terminals of each pair of telephone terminals for connection to one of the wireless terminals, a conductor, a plurality of telephone switches each adapted to connect

the second terminal of a pair of telephone terminals to said conductor, a choke coil, a condenser, and a control switch adapted in one position to connect the choke coil across 5 the pair of wireless terminals and the condenser in circuit between the second wireless terminal and said conductor and in another position to connect said conductor to the second wireless terminal and to put the 10 choke coil and condenser out of action.

4. Switch apparatus for use with telephonic receivers and wireless apparatus, comprising a support, pairs of insulated telephone terminals carried thereby, a pair 15 of insulated wireless terminals carried by said support, conducting means between one of the terminals of each pair of telephone terminals for connection to one of the wireless terminals, a conductor, a plurality of 20 telephone switches each adapted to connect the second terminal of a pair of telephone terminals to said conductor, a choke coil connected at one end to the first mentioned wireless terminal, a condenser having one 25 pole connected to said conductor and a control switch comprising three stationary contacts and a movable contact, one of the stationary contacts being connected to the second wireless terminal and to the second pole 30 of the condenser, another of the stationary contacts being connected to the second end of the choke coil and the third stationary contact being connected to said conductor, the movable contact in one position closing 35 a circuit between the first and secondly mentioned stationary contacts and leaving open a circuit between the first and third stationary contacts and in another position opening the circuit between the first and second 40 stationary contacts and closing a circuit between the first and third contacts.

5. Switch apparatus for use with telephonic receivers and wireless receiving apparatus, comprising a support, a panel of insulating 45 material carried by said support, a plurality of repairs of telephone terminals secured to said panel and external thereto, a pair of wireless terminals secured to said panel and exterior thereto, a conductor connected to 50 one of the telephone terminals of each pair thereof and adapted to be connected to one of the wireless terminals, a plurality of telephone switches secured to the inner side of said panel and each having two stationary 55 contacts and a movable contact, one of the stationary contacts being connected to the second terminal of a corresponding pair of telephone terminals, a second conductor connected to the second stationary contact of 60 each of the telephone switches and adapted to be connected to the other wireless terminal, levers extending through and pivoted to the panel and each carrying the movable contact of one of the telephonic switches, a 65 choke coil and a condenser, and a control

switch adapted in one position to connect the choke coil across the pair of wireless terminals and the condenser in circuit between the second wireless terminal and the said second conductor and in another position to connect said second conductor direct to said second wireless terminal and to put the choke coil and condenser out of action, said control switch being secured to the inner side of the panel and having an operating 70 lever extending through the panel to the outer side thereof.

6. Switch apparatus for use with telephonic receivers and wireless receiving apparatus, comprising a support, a panel of insulating material carried by said support, a plurality of pairs of telephone terminals secured to said panel and external thereto, a pair of wireless terminals secured to said panel and exterior thereto, a conductor connected to one of the telephone terminals of each pair thereof and adapted to be connected to one of the wireless terminals, a plurality of telephone switches secured to the inner side of said panel and each 80 having two stationary contacts and a movable contact, one of the stationary contacts being connected to the second terminal of a corresponding pair of telephone terminals, a second conductor connected to the second stationary contact of each of the telephone switches and adapted to be connected to the other wireless terminal, levers extending through and pivoted to the panel and each carrying the movable contact of 85 one of the telephonic switches, a choke coil having one end connected to the wireless terminal to which the first mentioned conductor is connected, a condenser having one pole connected to the secondly mentioned 90 conductor, and a control switch secured to the inner side of said panel and comprising three stationary contacts, a movable contact and an operating lever extending through said panel to the exterior thereof, one of the 95 stationary contacts of the said control switch serving for connection to the second wireless terminal of a pair thereof and to one pole of the condenser, another of the said stationary contacts serving for connection to the second end of the choke coil and the third stationary contact being connected to the secondly mentioned conductor.

7. Switch apparatus for use with telephonic receivers and wireless receiving apparatus, comprising a support, a panel of insulating material carried by said support, a plurality of pairs of telephone terminals secured to said panel and external thereto, a conductor connected to one of the telephone terminals of each pair thereof, a plurality of telephone switches secured to the inner side of said panel and each having two stationary 100 contacts and a movable contact, one of the stationary contacts being connected to the second terminal of a corresponding pair of telephone terminals, a second conductor connected to the second stationary contact of each of the telephone switches and adapted to be connected to the other wireless terminal, levers extending through and pivoted to the panel and each carrying the movable contact of one of the telephonic switches, a 105 choke coil and a condenser, and a control 110 switch adapted in one position to connect the choke coil across the pair of wireless terminals and the condenser in circuit between the second wireless terminal and the said second conductor and in another position to connect said second conductor direct to said second wireless terminal and to put the choke coil and condenser out of action, said control switch being secured to the inner side of the panel and having an operating 115 lever extending through the panel to the outer side thereof.

tacts and a movable contact, one of the stationary contacts being connected to the second terminal of a corresponding pair of telephone terminals, a second conductor connected to the second stationary contact of each of the telephone switches, levers extending through and pivoted to the panel and each carrying the movable contact of one of the telephone switches, a choke coil having one end connected to the first mentioned conductor, a condenser having one pole connected to the secondly mentioned conductor, a control switch secured to the inner side of said panel and comprising three stationary contacts, a movable contact and an operating

lever carrying the movable contact and extending through the panel to the exterior thereof, one of the stationary contacts being connected to the second pole of the condenser, another stationary contact being connected to the other end of the choke coil and the third stationary contact being connected to the secondly mentioned conductor, and interchanging switch mechanism whereby the telephone switches and associated parts can be connected across either pair of wireless terminals at will. 20 25

Signed at London, England, this eleventh day of January, 1926.

EDWARD ALFRED GRAHAM.
